UNITED STATES PATENT OFFICE.

JACOB L. NEIDLINGER, OF BLACKWOOD, PENNSYLVANIA.

GATE FOR ELEVATOR-LANDINGS.

1,263,921.

Specification of Letters Patent. Patented Apr. 23, 1918.

Application filed April 30, 1917. Serial No. 165,417.

To all whom it may concern:

Be it known that I, JACOB LEWIS NEIDLINGER, a citizen of the United States, residing at Blackwood, in the county of 5 Schuylkill and State of Pennsylvania, have invented certain new and useful Improvements in Gates for Elevator-Landings, of which the following is a specification, reference being had to the accompanying drawings.

This invention relates to certain improvements in gates for elevator landings and it is an object of the invention to provide novel and improved means whereby a gate 15 may be caused to assume an open position when the elevator approaches a landing and whereby said gate automatically assumes a closed position when the elevator moves away from the landing.

It is also an object of the invention to provide a device of this general character especially designed and adapted for use in connection with elevators or hoists in mining operation and wherein fans or arms are 25 employed to bring the hoist or elevator to a stop at a predetermined landing together with novel and improved means under control of the fans or arms whereby the elevator or hoist as it approaches the landing 30 causes the gate to assume an open position.

The invention consists in the details of construction and in the combination and arrangement of the several parts of my improved gate for elevator landings whereby 35 certain important advantages are attained and the device is rendered simpler, less expensive and otherwise more convenient and advantageous for use, all as will be herein-after more fully set forth.

The novel features of the invention will 40 hereinafter be definitely claimed.

In order that my invention may be the better understood, I will now proceed to describe the same with reference to the accompanying drawings, wherein—

Figure 1 is a fragmentary view partly in elevation and partly in section illustrating a gate structure arranged in accordance with an embodiment of my invention;

Fig. 2 is a view partly in section and partly in elevation of the gate structure as herein embodied and at substantially right angles to the disclosure in Fig. 1;

Fig. 3 is an enlarged fragmentary view 55 partly in section and partly in elevation illustrating one of the tubular members and

a shoe coacting therewith as herein embodied together with the parts coacting with the shoe;

Fig. 4 is a transverse sectional view taken 60 through a tubular member; and

Fig. 5 is a view partly in section and partly in top plan of the tubular member and the rock arm carried thereby.

As disclosed in the accompanying drawings, S denotes a guide structure for an elevator or cage C as generally employed in mine operations. L denotes a landing and pivotally supported by the structure S at opposite sides thereof and at a predetermined distance below the landing are the rock shafts 1 provided with the upstanding arms or fans 2 which, when swung inwardly, serve to limit the downward movement of the elevator or cage C so that the same will 75 be properly aligned with the landing L.

As herein disclosed, the structure S at opposite sides thereof and intermediate the shafts 1 is provided with the arm 3 pivotally mounted at substantially its longitudinal center. One end portion of the arm 3 is operatively engaged, as at 4, with an arm or fan 2 at one side of the structure S while the opposite end of the arm 3 is operatively engaged, as at 5, with an arm or fan 2 at 85 the opposite side of the structure S. By this arrangement it will be perceived that the shafts 1 will be rocked in unison but in reverse directions.

Coacting with each set of fans or arms 2 90 at a side of the structure S is a pivoted arm 6 operatively engaged with one of the connecting members, such as 5, and the upper end portion of said arm 6 is provided with an operating member 7 provided with a 95 hand grasp 8 whereby the arms or fans 2 may be manually operated to cause the same to assume an operative or inoperative position relative to the cage or elevator C.

The structure S is provided at opposite 100 sides of the landing L with the vertically disposed tubular members 9 provided with the elongated slots 10. The lower end of each of the tubular members 9 is rotatably engaged with an upstanding pin 11 suitably 105 supported by the structure S while the upper portion of the tubular member 9 is extended through an annular member 12 carried by a strip 14 also operatively engaged with the structure S at a predetermined 110 point above the landing L.

Loosely mounted within each of the tubu-

lar members 9 is a head or block 15 provided with a shoe 16 extending through the slot 10 and having its upper edge substantially horizontal. The lower portion of the tubular member 9 is provided with a rock arm 17 with which is pivotally engaged a rod 18 also operatively engaged with one of the fans or arms 2.

When the arms or fans 2 are moved inwardly to engage the elevator or cage C the tubular member 9 will be given a quarter turn so as to cause the shoe 16 to intersect the path of travel of the cage so that the same will be forced downwardly thereby.

The upper portion of the block or head 15 is provided with an extension 19 with which is pivotally engaged a clevis 20. Secured to the clevis 20 is a chain or other flexible member 21 which extends upwardly through the tubular member 9 and which is also directed through the coil spring 22 arranged within the tubular member 9. The spring 22 is provided at its opposite ends with the hook members 23 engaged with certain of the links of the chain whereby said chain is maintained taut.

The outer end of the chain or flexible member 21 is provided with a clevis 24 to which are engaged the chains 25 which extend in opposite directions and over the guide pulleys 26 suitably mounted upon the structure S. The chains 25 are engaged with the gates G mounted for vertical movement and whereby it will be perceived that as the shoe 16 is forced downwardly the gates G will assume an open position. It will also be self-evident that when the cage or elevator C moves upwardly the weight of the gates G will cause the same to move downwardly by gravity and assume a closed position.

While the chains 25 may be secured to the gates G in any desired manner, I prefer to have the chains engaged with the clevises 27 pivotally engaged with the upper marginal portions of the gates G adjacent the opposite ends thereof.

It is also to be noted that the gates G have their opposite end portions engaged within suitable guideways 28.

From the foregoing description, it is thought to be obvious that a gate for elevator landings constructed in accordance

Copies of this patent may be obtained for five cents each, by addressing the "Commissioner of Patents, Washington, D. C."

with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice, except as hereinafter claimed.

I claim:

In combination with an elevator and a shaft therefor provided with a landing, a vertically movable gate co-acting with the landing, a vertically disposed member mounted for swinging movement and movable into and out of the path of travel of the elevator for limiting the movement of the elevator within the shaft in one direction, a tubular member disposed in the same general direction as the shaft and mounted for rotary movement, said member being provided with a longitudinally directed slot, a block slidably engaged within said member and provided with a shoe extending through the slot of the tubular member, said shoe being adapted to extend within the line of travel of the elevator, a rock arm carried by said last named member, a rod pivotally engaged with the rock arm and operatively engaged with the vertically disposed member whereby swinging movement of the member serves to rock the rotatable member about its longitudinal axis, means for moving the vertical member into or out of the line of travel of the elevator, and a flexible connection between the block and the gate for moving said gate into an open position when the shoe is caused to move when engaged with the elevator, said flexible connection extending within the tubular member through the upper end thereof.

In testimony whereof I hereunto affix my signature in the presence of two witnesses.

JACOB L. NEIDLINGER.
